Primary Examiner — Elizabeth J Oswecki(74) *Attorney, Agent, or Firm* — Banner & Witcoff, Ltd.(57) **CLAIM**

The ornamental design for a shoe, as shown and described.

DESCRIPTION

FIG. 1 is a front bottom perspective view of a shoe showing my new design;

FIG. 2 is a bottom view thereof;

FIG. 3 is rear bottom perspective view thereof;

FIG. 4 is the front bottom perspective view of FIG. 1 with certain disclaimed environmental regions removed for clarity purposes;

FIG. 5 is the bottom view of FIG. 2 with certain disclaimed environmental regions removed for clarity purposes; and, FIG. 6 is the rear bottom perspective view of FIG. 3 with certain disclaimed environmental regions removed for clarity purposes.

The broken lines and unshaded regions depicting the remainder of the shoe show features that form no part of the claimed design.

1 Claim, 6 Drawing Sheets# US D985,246 S
